UNITED STATES PATENT OFFICE.

WILLIAM DUCHEMIN AND ALBERT JEFFERS, OF LYNN, MASSACHUSETTS.

IMPROVEMENT IN THE MANUFACTURE OF BOOTS AND SHOES.

Specification forming part of Letters Patent No. 68,320, dated August 27, 1867.

To all whom it may concern:

Be it known that we, WILLIAM DUCHEMIN and ALBERT JEFFERS, of Lynn, in the county of Essex and Commonwealth of Massachusetts, have invented an Improved Mode of Channeling the Soles of Boots and Shoes, for use in conjunction with a sewing-machine; and do hereby declare the following to be a full, clear, and exact description thereof, reference being had to the accompanying drawings, making part of this specification, and in which—

Figure 1 is a top view, and Fig. 2 a vertical section, of a portion of a sole as channeled by our process, and ready for application to the boot or shoe. Fig. 3 is a vertical section of such sole with the stitching inserted, and with the sole finished over such stitching. Fig. 4 is a representation of the old mode of channeling. Fig. 5 is a front view, Fig. 6 a side view, Fig. 7 a rear view, and Fig. 8 a vertical section, of the tool for forming the channel.

The object of this invention is not only to reduce the cost of manufacture of a boot or shoe to some extent, but to greatly improve its appearance, as well as its wearing qualities.

The invention consists, first, in the peculiar mode of forming the thread-receiving channel, and closing the leather down upon the stitching in such manner that the said stitching is compressed and reduced in bulk, and is buried within the leather, which is also compressed to such an extent as not to be exposed until the shoe or boot has been subjected to considerable wear, the sole also having a finished appearance, and the joint being imperceptible from the outside.

The invention further consists in the construction of the channeling-tool for forming the channel above referred to, substantially as hereinafter explained.

As shown in the accompanying drawings, A denotes the body of the said tool, it being a steel bar of proper size, the lower end of which is made into a form very much resembling a miniature land-plow in construction and operation, with the exception of a hollow cutter below it. Its extreme lower end is formed into a cutter, a, which is semicircular, or thereabout, in cross-section, and of considerable less width than the bulk of the bar, the metal above as well as in advance of such cutter

being made into a central beak or plowshare, b, and a mold-board, c, upon each side. A scoring-point or colter, d, is applied to the front face of the bar A, and in advance of the beak b, the object of such point being to score or crease the leather, and prepare the way for the action of the remaining portion of the tool.

The tool, made as above described, may be inserted in the ordinary channeling-machine.

The sole, under the action of the machine, is drawn along under the tool, which takes into it such a depth and in such manner that its cutter a shall cut a groove or channel, K, for receiving the thread or row of stitching, while its beak b and mold-boards c c throw up and compress the leather on each side of such channel into wrinkled edges or ribs m m, as shown in Fig. 1 of the drawings. The sole is now applied to the boot in the usual manner, and put into the sewing-machine, the stitching of which fills, or, rather, more than fills, the channel K. The boot is now removed from the sewing-machine, and subjected to the action of a compressing implement or machine of suitable construction, which passes over it in a direction opposite to that in which the channeling-tool traversed it, the action of such compressing implement having the effect of smoothing down, and returning to place, the edges m m, which meet and close over the row of stitching, and render the joining imperceptible from the outside. The action of the compressing implement also compresses the leather in all directions immediately about the stitching, and makes it, to some extent, homogeneous, and requiring no cement, and, further, makes a solid bearing-surface or tread to the sole. This compression, caused by the said implement, also serves to contract and reduce the chain-stitch, into which the thread is formed by the sewing-machine, and causes it to resemble in appearance and wear, and in non-liability to rip, the ordinary hand-stitch.

The ordinary way of channeling soles, when the boot is secured in a machine, is to cut and turn up from the outside edge of the sole a horizontal lip, l, (see Fig. 4 of the drawings,) and at the joining of the lip and sole to cut a channel, m', for the reception of the stitching, this lip l being subsequently returned to place and cemented in order to cause the parts to adhere together. Under the wear of the

boot and moisture this cement is destroyed, and, as is well known, the lip *l* separates from the sole in many cases, and leaves an unsightly, ragged edge to the boot. Further, more or less cement gets upon and adheres to the edge of the sole, and renders the subsequent operation of polishing or "slicking-up" the edge difficult and imperfectly performed.

The advantages of our mode of channeling are several: First, as before stated, the cost of manufacture is reduced, as the time employed in applying, as well as the expense of, the cement is saved; second, there is no liability, as in the old mode, of the lip separating from the sole and injuring the appearance of the boot, the wear or pressure upon the sole having a tendency rather to force the edges of the joint together; third, the stitching, as before stated, is compressed into such a shape as to very much reduce its bulk, and render it difficult, if not impossible, to ravel it, this being a very important feature in our invention; fourth, there is no cement employed; and, consequently, no possibility of smearing the

edge of the sole, and preventing it from receiving the proper finish and polish.

We do not claim a channel formed in the sole, having lips meeting over its center, for we are aware that the same has been patented to Charles H. Trash and Joseph B. Johnson under date of February 20, 1866; but our application is principally directed to the particular method of and means for throwing up the lips and forming the channel.

What we claim, therefore, and desire to secure by Letters Patent, is as follows:

The peculiar construction of the tool for forming the above-mentioned channel and turning its edges, consisting of the bar *A*, formed at its lower end into the cutter *a*, the beak or plowshare *b*, and the mold board or boards *c*, substantially in manner and to operate as specified.

WILLIAM DUCHEMIN.
ALBERT JEFFERS.
